UNITED STATES PATENT OFFICE.

VINTON E. SISSON, OF CHICAGO, ILLINOIS, ASSIGNOR TO WALTER P. MURPHY, OF CHICAGO, ILLINOIS.

METAL END FOR FREIGHT CARS.

Application filed October 1, 1920, Serial No. 414,053. Renewed June 9, 1922. Serial No. 567,194

To all whom it may concern:

Be it known that I, VINTON E. Sisson, a citizen of the United States, residing at Chicago, in the county of Cook and State of Illinois, have invented a new and useful Improvement in Metal Ends for Freight Cars, of which the following is a specification.

This invention relates to improvements in 10 end structures for railway cars and more particularly to sheet metal ends for freight cars.

The end of a freight car is subject to very 15 severe shocks and stresses on account of the tendency of the cargo to shift when the train starts and stops and in switching and also to the tendency of the superstructure of the car to weave while the train is in motion. To strengthen this type of car, ends have 20 been constructed of one or more sheets or panels of metal, usually steel, which sheets or panels are formed with corrugations for rigidifying the structure to more readily meet impacts from without, cargo thrusts 25 from within, and the racking strains from weaving.

It is the object of this invention to provide 30 an end of the sheet metal type which is adaptable to either wooden car frames or all metal freight cars and that may be employed for strengthening gondola cars, box cars, or other similar cars. It is a further object of this invention to provide the sheets or panels of the end with corrugations of 35 particular contour that from their form and duration are peculiarly adapted to meet the stresses and strains already described.

While the corrugations are preferably 40 formed parallel, their relation to each other or their direction is immaterial, likewise the corrugations may be all pressed from one side of the sheet of metal or may be formed from the opposite sides, as desired.

While the preferred form of this invention 45 is illustrated upon the accompanying sheets of drawings, yet it is to be understood that minor detail changes may be made without departing from the scope thereof.

In the drawings:

50 Figure 1 is a view in end elevation of a box car illustrating an embodiment of this invention.

Figure 2 is a view in horizontal section through the end taken on the line 2—2 of

Figure 1, illustrating the attachment of the 55 end to a car having a wooden frame.

Figure 3 is a view similar to Figure 2 illustrating the attachment of the end to an all metal box car.

Figure 4 is an enlarged detail view in 60 vertical section taken on the line 4—4 of Figure 1.

Figure 5 is an enlarged detail plan view 65 of a fragment of the corner of an end sheet or panel.

Figure 6 is an enlarged detail sectional view taken on the line 6—6 of Figure 5, looking in the direction of the arrows, with the parts beyond the line shown partly in perspective and partly in section. 70

The box car end, as illustrated, comprises two or more sheets or panels 1, preferably of pressed steel, which are attached to the corner posts, end plate and end sill in the usual manner. Figure 2 illustrates a means 75 of attaching the panels to a wooden corner post 2 by flanging the ends of the panel and securing the flanges to the post, while Figure 3 illustrates the attachment to an all metal car in which the corner post 3 is usually in 80 the form of an angle iron which secures the end in the manner shown.

A plurality of parallel strengthening corrugations are formed in each panel 1 and merged at their ends into the plane of the 85 panel so that the panel has a flat marginal portion about its edges.

The enlarged sectional view, Figure 4, clearly indicates the shape or contour of the corrugations, and from which it is seen 90 that each corrugation is formed with flat main walls 4 substantially at right angles to the plane of the panel connected by portions 5 which are semi-circular in cross section and tangent to the main walls. The 95 corrugations are similar and continuous and extend from opposite sides of the neutral axis of the panel. The semi-circular portions 5 having equal radii and being joined by the flat main walls 4 of equal depth, the 100 depth of a corrugation exceeds its width by the depth of the main walls.

A wooden end lining 6 is preferably provided on the inner side of the end and a plurality of filler blocks 7 are received 105 within and attached to a number of the corrugations, as shown, to which the wooden lining is nailed. The width of each corru-

gation is preferably constant throughout the greater part of its length and the depth also preferably remains constant throughout the greater part but gradually diminishes at each end until the corrugation merges into the plane of the panel, as shown in Figures 5 and 6.

In theory, the ideal form of corrugation for this purpose would have flat main walls 10 extending at right angles to the plane of the panel as having the greatest strength to resist the stresses imposed on car ends. In practice, in pressing corrugations from a panel by dies, it is very difficult to form the main walls in this relation. In the corrugation illustrated, from its peculiar contour, it is possible to form the main walls 4 substantially at right angles to the plane of the panel. The semi-circular portions 5 between the walls 4 act in the manner of an arch or bridge whereby stresses occurring at the apex are distributed through the curved portions to the main walls which, as above said, are most advantageously arranged to 20 meet such stresses. The majority of impacts received by the end of a car are from within and are caused by shifting of the cargo. The cargo thrusts are first received on the wooden lining 6 of the end and as this 25 lining is continuous and is in contact with the apices of the respective corrugations, the thrusts will be transmitted from the lining 6 through the curved portions 5 of the corrugations and be distributed through the main 30 walls 4.

What I claim is:

1. A metal panel for car ends having a plurality of corrugations formed therein, with the main walls of the corrugations parallel and formed substantially at right angles to the plane of the panel, and having semi-circular portions connecting said walls. 40
2. A metal panel for car ends having a plurality of corrugations of constant width throughout their major length formed therein, said corrugations having main walls formed parallel and substantially at right angles to the plane of the panel and having semi-circular portions connecting said walls. 45
3. A metal panel for car ends having a plurality of corrugations of constant width throughout their major length and merged 50

into the panel at the ends with the main walls of the corrugations formed parallel and substantially at right angles to the plane 55 of the panel, and semi-circular tangential portions connecting said walls.

4. A metal panel for car ends having a plurality of corrugations formed on alternate sides of the neutral axis of the panel 6 and having parallel main walls formed substantially at right angles to the plane of the panel, and having semi-circular portions connecting said walls, the depth of the corrugations exceeding their width. 65

5. A metal panel for car ends having a plurality of corrugations formed on alternate sides of the neutral axis of the panel and having parallel main walls formed substantially at right angles to the plane of the 70 panel, and having semi-circular portions tangentially connecting said walls, the depth of each corrugation exceeding its width by the depth of the main walls.

6. A metal panel for car ends having a 75 plurality of corrugations formed therein, with the main walls of the corrugations parallel and formed substantially at right angles to the plane of the panel, and having semi-circular portions connecting said walls, 80 said corrugations terminating within the edge of the panel.

7. A metal panel for car ends having a plurality of corrugations of constant width 85 throughout their major length formed therein, said corrugations having main walls formed parallel and substantially at right angles to the plane of the panel and having semi-circular portions connecting said walls, 90 said corrugations terminating within the edge of the panel.

8. A metal panel for car ends having a plurality of corrugations formed on alternate sides of the neutral axis of the panel and having parallel main walls formed substantially at right angles to the plane of the panel, and having semi-circular portions tangentially connecting said walls, the depth of each corrugation exceeding its width by the depth of the main walls, said corrugations terminating within the edge of the 100 panel.

VINTON E. SISSON.
